ENVELOPE SEALING MACHINE

William H. Bryson, Savannah, Ga.

Application April 23, 1935, Serial No. 17,881

6 Claims. (Cl. 91—51)

This invention relates to an envelope sealing device wherein a plurality of unsealed envelopes are individually and positively fed through a machine which moistens the adhesive on the flap of the envelope and seals the moistened flap against the body portion.

An object of the invention is to construct an envelope sealer which will be positive in its action of feeding the bottom envelope from a pile of envelopes arranged in a magazine; which will convey the individual envelopes past a moistener with the envelope flaps upturned at an angle of 90°; and which will thereafter fold the flap down and seal it against the envelope body portion.

Another object of the invention is to provide a rotatable moistener driven by the envelopes passing therethrough which will coat the adhesive on the flap of the envelope with a thin uniform film of water.

A still further object of the invention is the construction of a pick-up device which intermittently passes beneath the pile of envelopes to be sealed and removes only the bottom envelope from the pile.

In the drawings, Fig. 1 is a side elevation of the complete machine.

Fig. 2 is a vertical section taken on line 2—2 of Fig. 3.

Fig. 3 is a top plan view of the complete machine with a portion of the moistening mechanism broken away.

Fig. 4 is a horizontal cross-section taken on line 4—4 of Fig. 1.

Fig. 5 is an enlarged vertical cross-section showing the moistening roller and fountain.

Fig. 6 is a vertical cross-section taken on line 6—6 of Fig. 1 looking toward the end of the magazine.

Figs. 7, 8, 9, and 10 are enlarged detail views of the envelope pick-up device.

Fig. 11 is a fragmental vertical section of the sealing rollers taken on line 11—11 of Fig. 1.

More specifically in the drawings, 1 indicates a cast or pressed metal base plate on which is mounted a cast or pressed metal casing 2 which supports the envelope magazine, flap moistener and fixed flap folder. Attached to the base plate 1 interiorly of the casing 2 is a plate 3 formed with integral upstanding pairs of spaced arms 4, 5, and 6; while mounted in slots formed in the upper ends of the pairs of arms 4 and 5 are horizontal axles 7 and 8 respectively. These horizontal axles 7 and 8 carry grooved pulley wheels 9 and 1 and in their peripheries a V-shaped flex-

ible belt 11 is looped. Power is applied to the belt 11 through the medium of pinion 12 which is affixed to pulley 10 and is carried on axle 7. In turn, axle 7 receives rotation from gear 13 affixed to shaft 14 of motor 15.

While not essential to the successful operation of the machine, it is desirable to use a constant speed electric motor of small power. Consequently, instead of varying the speed of the motor, a governor 10 is attached to shaft 8. This governor may be of any desired form, although the conventional centrifugal weight type having a brake 11 controlled by movement of thumb-screw 12 has been found most satisfactory.

It will be obvious to those skilled in the art that a hand-crank may be readily substituted for the electric motor and that without any change in principle the machine may be efficiently operated by rotation of this hand-crank.

A second pulley wheel 16 also is secured to shaft 8 and is mounted adjacent pulley wheel 9. 20 Carried between the end vertical brackets 6 is a horizontal axle 17 on which is mounted roller 18 having a rubber, cork, or other composition surface 19. This roller 18 is driven by pulley 20 which receives power through belt 21 running over pulley 16. The diameter of drive pulleys 16 and 20 is somewhat smaller than that of pulleys 9 and 10. Consequently, the speed of driven roller 18 is greater than the speed of driven pulleys 9 and 10. The purpose of this faster moving roller will be hereinafter described in detail.

An elongated slot or opening 22 slightly wider than the width of belt 11 is formed in the top of casing 2. As will be seen in Figs. 2 and 3, this slot 22 extends from adjacent the right-hand end of the top of the casing 2 throughout the major distance thereof. A vertical, open-front, oblong, sheet-metal magazine or hopper 23 is mounted on the top of casing 2 directly over slot 22 and is detachably secured thereto by depending fingers 24 which cooperate with openings 25 formed in the top surface of the casing. To accommodate various sized envelopes larger sized magazines may be readily attached to the casing as illustrated by dotted lines 25 (see Fig. 3). An adjustable longitudinal guide 80 is secured to the top edge of the casing by adjustable thumb-screw 81. Depending lugs 82 registering with openings in the top of the case are formed near the ends of the guide for the purpose of holding the inner edge of the envelope as it passes out through the magazine on the way to the moistener. The adjustability of the guide permits its use on any size magazine.

Referring to Fig. 6 it will be seen that one end of the magazine or hopper 23 is provided with a bottom opening 26 through which the body portions of the envelopes are fed. The opening 26 also extends upwardly at 27 to accommodate the flap of the envelope as it is withdrawn from the hopper. A resilient forked sheet-metal, horizontal guide 28 extends from the top of opening 26 outwardly and downwardly to insure that the envelopes as fed from the magazine are held in a horizontal position against the top of the casing.

Affixed to drive belt 11 are a plurality of spaced envelope pick-up devices 29. These pick-up devices lie transversely across the belt and comprise a pivoted upstanding finger member 30 attached to an offset base 31 by means of horizontal hinge pin 32. A weak coil spring 33 encircling a portion of the pivot pin bears against the hooked finger 30 and base 31 so that in normal position the hook is held upright. The finger 30 has a forwardly extending hook or bill 34 and a lower horizontal cam face 35.

This pick-up assembly is one of the salient features of the present invention, as it insures the positive feeding of the lowermost envelope of the horizontally arranged pile contained in the magazine. Through this mechanism the envelopes are individually and positively projected through bottom opening 26, one at a time, regardless of their thickness.

As before stated, a pile of envelopes to be sealed are placed in the hopper 23 with their flaps upturned and overlapping. When power is applied to belt 11 the spaced pick-ups 29 move from right to left in the opening 22 so that the right hand edge of the bottom envelope strikes upon cam face 35 which lifts the edge of the envelope and pivots the upper portion of the finger 30 backwardly against the tension of the weak coil spring 33, this action being illustrated in Fig. 7. As the edge of the bottom envelope is elevated by the cam, it is projected to the left by contact with the hook portion 34. The inward curvature of the hook 45 makes it impossible to hold more than one envelope. Continued movement of the belt forces the envelope outwardly from the hopper and, as shown in dotted lines in Fig. 6, the upturned flap passes out through vertical opening 27. Affixed to the end of the hopper and lying between vertical opening 27 and resilient guide 28 is a hinge member 36 having an offset lug 37 projecting into the bottom of opening 27. Normally the hinge 36 is pressed downwardly by spring strap 38. This hinge member cooperates with the pick-up fingers to bear against the envelopes as they are forced from the magazine and positively controls the feeding of individual envelopes therefrom. The space between the top of the casing and the bottom of hinge 36 is sufficient to just allow the passage of the leading edge of the envelope therethrough.

Spaced from the rear edge of the hopper or magazine 23 is an upstanding fixed guide plate 40 whose end nearest the magazine is slightly flared as indicated at 41 and, as shown in Fig. 2, is also outwardly curved at 42 to accommodate the outer periphery of the moistening device which will be hereinafter described. The other end of the guide 40 is bent inwardly and over on an oblique angle at 43 and terminates just short of roller 18.

A vertical bracket 44 is secured to the edge of the casing 2 directly behind the curved section 42 of the fixed guide member 40. Fastened to

the top of bracket 44 at the side thereof adjacent flared edge 41 is a depending vertically spaced flap guide 45.

A moistening attachment also is supported from the top of bracket 44 and consists of an obliquely depending strap 46 which terminates in an internally screw-threaded cylindrical base 47. An integral journal bearing 48 is formed in the strap member 46 and through the bearing opening 49 carries an axle 50 which is mounted at an angle 10 and is outwardly secured by a pin 51 passing through a rotatable end plate 52. The opposite end of the axle 50 is secured to a cone member 53 whose outer surface is covered with a thin layer of rubber or other suitable material 54. Screw-threaded in the cylindrical base 47 is a water or solvent bottle 55 provided with a spring-pressed closure valve 56. The outwardly extending valve stem 57 of the valve 56 contacts with a shallow fountain plate 58 which is attached to the bottom of and slightly spaced below the cylindrical base 47. When in position the bottle is always open. As shown in Fig. 5 the fountain plate extends inwardly towards the bracket 44 so that the lower surface of the cone 53 is always moist. 23

Offset brackets 60 carrying vertical pins 61 are riveted or otherwise secured to the upper ends of the spaced brackets 6. A freely floating roller 62 having a resilient covering 63 is mounted on axle 64, the ends of the axle being perforated and carried on the pins 61. The roller 62 is held in resilient contact with lower roller 18 through the medium of coil springs 65 surrounding the upper portions of the pins 61 and bearing against the ends of the axle. A washer 66 and pin 67 hold the assembly in position. 30

In operation the envelopes are fed by the power belt and pick-up device outwardly from the magazine with their flaps upstanding, the spring fingers 28 hold the body portion of the envelope 40 against the top of the casing 2, while the flaps are directed between the curved plates 41 and 45. Continued movement of the envelopes brings the outside of their flaps into contact with the outwardly curved portion 42 of the vertical guide 40; 45 while the inside of the flap having the adhesive thereon contacts the rubber surface 54 of the cone. This frictional contact rotates the cone to present a wet portion thereof against the adhesive to moisten it. As the envelopes are fed further, the 50 upstanding moistened flap is folded over by the inwardly bent fixed guide 43 which initially forced the moistened flap against the body portion of the envelope. At this point the edge of the envelope has been pressed between the rollers 18 and 62 55 and, as the bottom roller is running at a comparatively high rate of speed, the envelope is forcibly pulled between the rollers and ejected from the machine in a completely sealed condition. 60

What I claim is:

1. In an envelope sealing device a magazine for holding a pile of horizontally arranged unsealed envelopes having their flaps upturned and lying in a vertical plane, a driven belt passing underneath said magazine, horizontally pivoted pick-up fingers attached to said belt adapted to segregate the lowermost envelope from said pile and propel it outwardly from said magazine, and fixed vertical guides directing the vertically upturned flaps of said propelled envelopes into engagement with a moistening device. 65

2. In an envelope sealer, a magazine for unsealed envelopes, a power driven belt passing immediately beneath said magazine, upstanding 70

- pivoted fingers affixed to said belt and adapted to contact with and remove the lowermost envelope in the said magazine, and thereafter convey the unsealed envelope through a flap-moistening device wherein moisture is applied to the adhesive on the flap of said envelope.
3. In an envelope sealing device, a magazine adapted to support a plurality of horizontally arranged unsealed envelopes having their flaps 10 upturned and overlapping, a driven belt arranged beneath said magazine, a plurality of upstanding horizontally pivoted pick-up fingers pivotally attached to said belt and adapted to contact with the lowermost envelope in the said magazine and remove it therefrom, the said fingers having front cam surfaces upwardly terminating in a forwardly extending hook adapted to contact the end of the envelope as it is fed from the magazine and a fountain moistening device 15 including a rotatable cone whose moistening surface lies in a perpendicular plane for applying moisture to the vertically upturned flap of the envelope.
4. In an envelope sealer, a magazine for holding a plurality of unsealed envelopes, the said envelopes lying in said magazine in a horizontal layer with their flaps vertically upturned and overlapping, a horizontal power driven belt positioned beneath the magazine, an upstanding pivoted pick-up affixed to said belt adapted to project the lowermost envelope of said layer from said magazine and carry the same in the direction of the longitudinal flight of said belt, an offset guide mounted adjacent the said belt and positioned outside of the magazine to engage the vertically upturned flap of the envelope as it is moved by the belt, and a moistening device rotated by the movement of the envelope adapted to apply moisture to the adhesive portion of the envelope flap.
5. In an envelope sealing machine, a hopper, 5 an endless belt, a moistening fountain, said fountain comprising a 90° rotatable cone having its axis set on a 45° angle and having a resilient covering on its periphery, a shallow pan supported below said cone into which the cone 10 covering dips, and a fountain bottle supplying solvent to said pan, the said belt conveying unsealed envelopes past said cone with the unsealed flaps thereof contacting the vertical plane of the cone.
6. An envelope sealer including a casing, an envelope magazine mounted on the top of and adjacent one end of said casing, an elongated opening in the top of said casing, a portion of which underlies the said magazine, a power 20 driven endless belt riding in said opening, staggered pick-up fingers attached to the outer surface of said belt, a horizontal opening formed in the lower side of the magazine adjacent the surface of the casing, said horizontal opening 25 having a vertical continuation adjacent one side of the magazine, a horizontal spring-pressed gate normally obstructing a portion of both the horizontal and vertical end opening, the said pick-ups on the endless belt contact with and 30 project envelopes through the said magazine end opening with the body portion passing through the horizontal opening and the flap of the envelope passing through the vertical continuation of the opening.

WILLIAM H. BRYSON.
